UNITED STATES PATENT OFFICE.

HUGH F. HURST, OF RICHMOND, VIRGINIA.

LABEL PRINTING OR STAMPING MACHINE.

1,374,374.

Specification of Letters Patent. Patented Apr. 12, 1921.

Application filed June 3, 1920. Serial No. 386,341.

To all whom it may concern:

Be it known that I, HUGH F. HURST, a citizen of the United States, residing at Richmond, in the county of Henrico and State of Virginia, have invented certain new and useful Improvements in Label Printing or Stamping Machines, of which the following is a specification, reference being had to the accompanying drawings.

10 This invention relates to the art of printing and more especially to a machine for printing or stamping labels.

Druggists as a rule have on hand fifty or sixty labels more or less which carry only the name of the medicine for which the labels are intended, such as sulfur-ammonia water, etc. Some of the labels have printed thereon "Essence of lemon" and on the second line "Alcohol 90 per cent," 20 and other labels carry only the dosage such as "Castor oil" on one line and on a second line "One tablespoonful." Then wholesale druggists have printed on the labels the name only such as "F. E. cascara," spirits 25 of camphor, bay rum, etc., and no other particulars. Frequently some druggists use blanks and write on each blank, at the time needed, the medicine for which the blank label is intended. Such labels are often 30 poorly written and are liable to cause serious mistakes. Druggists who keep a supply of labels are also handicapped in having their money tied up and especially in 35 keeping such labels in a readily accessible manner.

The present invention aims to avoid these disadvantages and to provide a machine for printing the labels as they are needed thereby greatly reducing the expense of having 40 labels printed and keeping a great number of labels of each medicine on hand.

Another object is to provide a machine in which each blank label as it is needed to be placed on the bottle of medicine is inserted so that by moving a printing member 45 or cylinder downward the label may be printed and then the label drawn through the machine and torn off, leaving another label in place.

50 Still another object is to provide a machine of this kind whereby the printing member or cylinder may be adjusted or rotated so as to position a different line of type opposite the platen roller so that the

label which is left in place can be printed 55 with an entirely different name.

A further object is to provide a machine of this character which can perform the work of printing the labels as they are needed efficiently and very quickly, it being 60 obvious that the machine is at all times ready for use, owing to there being a supply or roll of labels mounted on the side of the machine with certain of the labels protruding transversely of the machine in a 65 position opposite the platen roller.

A still further object is to provide a printing ribbon and a mechanism for automatically feeding it over the platen in either direction, in other words, the ribbon is capable of being reversed so that the ribbon 70 can run back and forth from one roller to another, in combination with manual means to permit the ribbon to be fed at different times.

The invention also aims to provide a 75 guide for the label as it passes over the platen roller.

Also the invention aims to provide means for holding the printing cylinder in different positions, there being a casing inclosing the mechanism, in order to indicate when the name of a certain medicine is opposite 80 the platen roller so that by simply depressing the cylinder, the impression of the name 85 may be applied on the label.

While the design and construction at present illustrated and set forth is deemed preferable, it is obvious that as a result of a 90 reduction of the invention to a more practical form for commercial purposes, the invention may be susceptible to changes, and the right to these changes is claimed, provided they are comprehended within the scope of what is claimed.

The invention comprises further features and combination of parts, as will be hereinafter set forth, shown in the drawings and claimed.

In the drawings:—

Figure 1 is a view in perspective of the improved label printing device constructed in accordance with the invention,

Fig. 2 is a vertical sectional view on line 2—2 of Fig. 1,

Fig. 3 is a transverse sectional view on line 3—3 of Fig. 2, showing the platen roller and illustrating the guide for the label,

Fig. 4 is a view in elevation of one side of the machine opposite to that shown in Fig. 1.

Fig. 5 is an enlarged detail view of the 5 guide for the label; and

Fig. 6 is a detail perspective view of the spring arm 51.

Referring to the drawings, 1 designates the base of the machine which may be any 10 suitable shape or configuration and rising upwardly from the base or the side uprights 2, the upper ends of which are connected by the cross piece 3. The base 1 is provided with a transverse cavity 4 and arranged 15 therein is a platen roller 5. One end of the cavity has a bearing 6 for the pintle 7 of the platen roller. The other end of the shaft 8 of the platen roller has a reduced extension 9, which is mounted in a bearing 20 of the plate 10, which is secured to the side edge of the base 1 by means of screws 11. Positioned on the base adjacent and over the platen roller is a label guide 12. This 25 label guide is constructed of a single piece 25 of sheet metal bent upon itself as at 13, and the bent portions or parts thereof are provided with elongated rectangular openings 14, which extend transversely of the base. One edge of the sheet metal forming 30 the guide has an over-turned flange 15 under which the edge portion 16 of the other bent or folded part of the guide engages thereby holding the opposite parts of the guide in position. One end of this guide is provided 35 with spaced ears 17 which receive screws to secure the guide on the base. The other end of the sheet metal guide has a projecting ear 18, which is secured at 19 to the plate 10. It is obvious that by first removing 40 the screws from the lugs or ears 17, and by removing the screw 19, the sheet metal guide may be removed. If necessary, the plate 10 may be detached with the guide by first removing the screws from the lugs or 45 ears 17 and then detaching the plate 10. When this means is employed for removing the guide it is obvious that the platen roller may be detached, so that it can be repaired or a new one inserted. The lower part of 50 one of the uprights 2 is cut away and thereby providing an opening 20 which is positioned adjacent one end of the sheet metal guide so as to assist in guiding the label into and through the guide.

55 The base 1 is provided with oppositely arranged elongated slots or openings 21, in bearings of the end of which the pintles of the ribbon rolls 22 are mounted. The ribbon 23 engages about said rolls, and the rolls for 60 the ribbon are capable of rotating so as to feed the ribbon back and forth across the label guide. One end of each of the ribbon rolls is provided with ratchet teeth 23a. These ratchet teeth are protected by the 65 plates 24 carried by the pintles of the ribbon

rolls and secured to the ends of the rolls so as to insure guiding the detent ends of the escapement detent 25 in engagement with the ratchet teeth of the rolls.

Mounted in bearings of the uprights 2 is 70 a printing cylinder, die or member 26. This cylinder is mounted upon a shaft to rotate therewith and one end of the shaft 28 has a hand knob 27 by which the cylinder may be rotated for adjusting certain lines of type 75 to position opposite the platen roller. This shaft is movable in guide slots 29 of the uprights. Pivoted on one end of the shaft is the escapement detent 25 comprising the two arms 31 and 32. The arm 31 is in a position to engage the ratchet teeth of one of the ribbon rolls while the arm 32 is in a position to engage the ratchet teeth of the other ribbon roll, when the detent is set. A lever 33 is pivoted at 34 to one of the uprights 85 and is provided with a handle 35. The other end of the lever is extended downwardly and terminates at a point substantially intermediate the two arms 31 and 32 of the escapement detent, and connected to the end as at 90 36 is a pair of coil springs 37.

The remote ends of the springs are connected at 38 to the arms 31 and 32 of the escapement detent so as to tension the same and hold either one of its arms in position 95 relatively to its respective ratchet teeth of the respective ribbon rolls. It will be seen that by setting the lever 33 in one position so as to position the tooth 39 of the arm 32 of the detent in close position to the ratchet 100 teeth of one of the ribbon rolls, the arm 32 is under tension of one of the springs so that when the ribbon roll is moved for adjusting the ribbon, the tooth 39 will engage and disengage the ratchet teeth. In other words, 105 the roll with the teeth of which the tooth 39 coöperate will be prevented from backward movement. When it is desired to feed the ribbon in an opposite direction, the other roll may be rotated and in this instance the 110 tooth 40 of the arm 31 of the detent will ride over the ratchet teeth of the other roll, and prevent retrograde movement of the roll. When one ribbon roll is accomplishing the feed of the ribbon, the ribbon 115 unreels from the other roll, because the tooth of the detent is free of the teeth. The lever 33 is provided with a hand grip operated dog 41 for holding the lever in position. The printing cylinder is constructed of 120 metal, and in order that the printing cylinder may be moved vertically its shaft is mounted in bearings of the arms of a U-shaped frame 42, which is mounted in guides 43 of the side uprights 2. A rod 43a is fixed 125 to the transverse part of the U-shaped frame and is guided through a bearing in the cross-piece 3 and has a knob at its upper end. Interposed between the knob 44 of the rod 43a and the cross piece 3 and in surround- 130

ing relation to the rod is a coil spring 45, which acts to hold the U-shaped frame in a raised position, therefore, holding the printing cylinder in a raised position.

5 The perimeter of the printing cylinder is provided with a plurality of transverse grooves 46 in which type bars 47 are inserted. These type bars have the usual type faces which are adapted for printing the 10 names of different medicines, for instance such as turpentine, essence of lemon, sulfur-ammonia water, castor oil, gasoline, bay rum, etc. Also on the perimeter of the cylinder adjacent one side there are printed names 15 48 corresponding to the names of the type bars. These names 48 are arranged so that they are visible through the transparent covered opening 49 of the casing 50. A spring arm 51 is secured to the cross piece 20 3 and terminates in a laterally extending indicator or point 52. The names printed on the perimeter of the cylinder adjacent one side are so arranged relatively to the type bars that when a certain type bar is in position to make an impression on the label, the 25 corresponding name of the perimeter of the cylinder is opposite the indicator or point 52. In other words, when the name of a certain medicine is opposite the pointer or 30 indicator 52 the type bar with a corresponding name is opposite the platen roller thereby indicating when a certain type bar is in proper position to make an impression on the label. In order to hold the cylinder in 35 such a position according to the type bar to be impressed on the label a roller detent 54 is mounted in ears of the spring arm 51, and is designed to engage any one of the plurality of depressions 55 of the perimeter of the 40 cylinder.

The casing 50 houses the mechanism, and this casing 50 comprises the two hood sections 56 and 57, and the hood section 56 is fixed in position by means of the screws as 45 illustrated, while the hood section 57 is hinged at 58 to the cross piece, and is capable of being moved upwardly so as to have access to the ribbon and the ribbon rolls and also to the label guide. However, access 50 may be had to one end of the label guide through an opening 60 formed in one of the uprights and which opening 60 is closed by a closure 61, and this closure 61 has a slot 62 therein so as to permit the label to be 55 pulled from the guide after it is printed.

A pair of bracket arms 63 is secured to one side of one of the uprights 2 and journaled in bearings of these arms is a label carrying cylinder 64. The labels are 60 constructed in the form of a strip, one face of which is supplied with adhesive material, while the other face is printed to provide label faces at spaced intervals. The strip of paper is inserted through the label guide,

with the adhesive face adjacent the platen 65 roller. The strip of paper is fed through the guide so as to position the label in the proper place so that an impression of a certain type bar may be made through the ribbon which passes over one of the slots of the 70 guide. After the label has been placed it is obvious that by pushing down upon the knob of the rod 43 of the U-shaped frame 42 the cylinder is lowered to make an impression of the type bar on the ribbon, which in turn causes an impression of the name of the type bar on the label. After the label is printed it may be pulled through the guide and torn off, owing to the knife edge 66. When the label has been severed, another 80 label is left in position to be printed.

This machine may be used for printing strips other than label strips, and also may be used for printing cards and the like.

The ribbon rolls have additional ratchet 85 teeth 70 and 71, which are engaged by the dogs 72 and 73. The ribbon is fed from one roller to another when the printing cylinder is depressed. For instance, the escapement detent is set by positioning the lever 90 so that one or the other of the teeth of the arms of the detent may assume a position to engage the first ratchet teeth of the respective ribbon roller after which the cylinder may be depressed. The tooth of the detent 95 will slide over the first ratchet teeth and engage certain of the ratchet teeth, the dog 72 acting to prevent the ribbon roller from rotating in a retrograde direction, then when the cylinder is allowed to resume its 100 normal position the teeth of the detent will feed the ribbon roller forward. This same action occurs when the other arm of the escapement detent is set so that its other tooth will coöperate with the ratchet teeth of the 105 roller. In this way, the ribbon is fed automatically from one roller to the other in either direction.

The invention having been set forth, what is claimed as new and useful is:—

1. In a label printing machine, a frame having a base, a platen roller journaled in bearings of the base, a label guide positioned over the platen roller and provided with upper and lower openings and through 115 which the label passes, said guide being constructed of a single piece of sheet metal bent upon itself causing to be formed the upper and lower parts which have said openings, a printing ribbon extending across the guide 120 over the face of the label, and a printing member movable in guides of the frame and adapted when depressed to cause an impression of a type bar on the label.

2. In a label printing machine, a frame 125 having a base, a platen roller journaled in bearings of the base, a label guide positioned over the platen roller, said guide being con-

structed of a single piece of sheet metal and comprising upper and lower parts having rectangular elongated openings, a ribbon arranged over the guide, a printing cylinder 5 having type bars therein movable in guides of the frame, and adapted when depressed to complete an impression of one of its type bars on the label.

3. In a label printing machine, a frame 10 having a base, a platen roller journaled in bearings of the base, a label guide positioned over the platen roller, said guide being constructed of a single piece of sheet metal and comprising upper and lower parts having 15 rectangular elongated openings, a ribbon arranged over the guide, a printing cylinder having type bars therein movable in guides of the frame, and adapted when depressed to cause an impression of one of its type bars 20 on the label, and means to indicate when a certain type bar is in position to make an impression on the label.

4. In a label printing machine, a frame having a base, a platen roller journaled in 25 bearings of the base, a label guide positioned over the platen roller, said guide being constructed of a single piece of sheet metal and comprising upper and lower parts having rectangular elongated openings, a ribbon arranged over the guide, a printing cylinder 30 having type bars therein movable in guides of the frame, and adapted when depressed to cause an impression of one of its type bars on the label, and means for holding the cylinder 35 in position with a type bar in relatively close position to the label whereby an impression of the type bar may be made.

5. In a label printing machine, a frame having a base, a platen roller journaled in 40 bearings of the base, a label guide positioned over the platen roller, said guide being constructed of a single piece of sheet metal and comprising upper and lower parts having rectangular elongated openings, a ribbon arranged over the guide, a printing cylinder 45 having type bars therein movable in guides of the frame, and adapted when depressed to cause an impression of one of its type bars on the label, and means to indicate when a 50 certain type bar is in position to make an impression on the label, said cylinder being rotatably mounted, and means for holding the cylinder against rotation while the cylinder is being depressed to cause an impression 55 of the type bar on the label.

6. In a label printing machine, a frame comprising a base and side uprights, a label receiving means carried by the base extending transversely under the cylinder, a platen 60 roller under said label receiving means, a ribbon operative over the label receiving means, and a printing member movable vertically and operatively in bearings of the side uprights, and having type bars, any one 65 of which may engage the ribbon and cause

an impression of the type bar on the label when the printing member is depressed.

7. In a label printing machine, a frame comprising a base and side uprights, a label receiving means carried by the base, a platen 70 roller under said label receiving means, a ribbon operative over the label receiving means, and a printing member movable vertically and operatively in bearings of the side uprights, and under which the label receiving means is transversely disposed, said cylinder having type bars, any one of which may engage the ribbon and cause an impression of the type bar on the label when the printing member is depressed, and means 80 for returning the printing member to initial position.

8. In a label printing machine, a frame comprising a base and side uprights, a label receiving means on the base, a platen roller 85 thereunder, a ribbon arranged over the label receiving means, a U-shaped frame mounted in guides of the side uprights, a printing cylinder under which the label receiving means transversely extends, said cylinder 90 having its perimeter provided with type bars being journaled in bearings of the U-shaped frame, said U-shaped frame being movable downwardly to cause the impression of a certain type bar of the cylinder on 95 the label, and means for automatically returning the cylinder to its initial position.

9. In a label printing machine, a frame comprising a base and side uprights, a label receiving means on the base, a platen roller 100 thereunder, a ribbon arranged over the label receiving means, a U-shaped frame mounted in guides of the side uprights, a printing cylinder having its perimeter provided with 105 type bars and journaled in bearings of the U-shaped frame, said U-shaped frame being movable downwardly to cause the impression of a certain type bar of the cylinder on the label, and means for automatically returning the cylinder to its initial position, 110 means for supporting the cylinder and in which said cylinder is rotatably mounted, and a detent carried by the cylinder supporting means and adapted to engage with the perimeter of the cylinder for holding it 115 against rotation, while a certain type bar is in position above the platen roller.

10. In a label printing machine, a frame, a label receiving means on the bottom of the frame, a platen member under the label 120 receiving means, a ribbon positioned movably across the label receiving means, rolls between and about which the ribbon operatively connects, whereby the ribbon can be moved back and forth across the label receiving means, an escapement detent mechanism for holding one or the other of the rollers against retrograde movement in feeding the ribbon in one direction, and a printing cylinder having type bars movably 125 130

mounted in the frame to make impressions on the labels as they are fed under the ribbon.

11. In a label printing machine, a frame, spaced rolls mounted in bearings of the bottom of the frame, a ribbon operatively connecting said rolls whereby the ribbon may be moved in one direction or the other, an escapement detent adapted to be positioned to prevent retrograde movement of either one of the rolls, a label receiving means and platen under the ribbon so that the ribbon can be adjusted thereacross, a printing cylinder relatively superimposed to the ribbon whereby a type bar thereof may make an impression through the ribbon on the label when the cylinder is depressed.

12. In a label printing machine, a frame, spaced rolls mounted in bearings of the bottom of the frame, a ribbon operatively connecting said rolls, whereby the ribbon may be moved in one direction or the other, an escapement detent adapted to be positioned to prevent retrograde movement of either one of the rolls, a label receiving means and platen under the ribbon so that the ribbon can be adjusted thereacross, a printing cylinder relatively superimposed to the ribbon whereby a type bar thereof may make an impression through the ribbon on the label when the cylinder is depressed, a cylinder supporting member mounted in guides of the frame and in bearings of which the cylinder is rotatably mounted, a stem carried by said cylinder supporting means and engaging a guide of the frame, means co-operating with the stem to raise the cylinder to a normal position after making an impression of the type bar.

13. In a label printing machine, a frame, spaced rolls mounted in bearings of the bottom of the frame, a ribbon operatively connecting said rolls, whereby the ribbon may be moved in one direction or the other, an escapement detent adapted to be positioned to prevent retrograde movement of either one of the rolls, a label receiving means and platen under the ribbon so that the ribbon can be adjusted thereacross, a printing cylinder relatively superimposed to the ribbon whereby a type bar thereof may make an impression through the ribbon on the label when the cylinder is depressed, a cylinder supporting member mounted in guides of the frame and in bearings of which the cylinder is rotatably mounted, a stem carried by said cylinder supporting means and engaging a guide of the frame, means co-operating with the stem to raise the cylinder to a normal position after making an impression of the type bar, and detent means for holding the cylinder against rotation when the cylinder is moved vertically downwardly to make an impression.

14. In a label printing machine, a casing, a printing mechanism therein, ribbon carrying rolls mounted in the base of the casing, a ribbon engaging said rolls and adapted to be wound from one to the other, ratchet teeth on corresponding ends of said rolls, an escapement detent having diverging arms and being pivotally mounted on the casing, said arms terminating in teeth and means operatively connected with the detent for causing the teeth of the arms to co-operate with the ratchet teeth of the rolls to impart an intermittent motion to said rolls, thereby unreeling the ribbon from one roll and feeding it upon the opposite roll.

15. In a label printing machine, a casing, a printing mechanism mounted therein, ribbon supporting rolls mounted in the casing, a ribbon engaging said rolls, a forked escapement detent pivotally mounted upon the casing, the forks of which are adapted to operatively connect alternately with the rolls for feeding the ribbon from one roll to the other, and a lever having yieldable connections with the forks of the detent, for operating the detent.

16. In a label printing machine, a casing, a printing mechanism mounted therein, ribbon supporting rolls mounted in the casing, a ribbon engaging said rolls, a pivoted forked detent having one or the other of its forks co-operatively connecting with one of the rolls for imparting an intermittent motion thereto, and a single lever operatively connected with the detent for shifting the same whereby one or the other of the rolls may be given an intermittent motion.

17. In a label printing machine, a casing, a printing mechanism therein, ribbon supporting rolls mounted in the casing, a ribbon engaging said rolls, ratchet means for the rolls to prevent retrograde movement thereof, a forked escapement detent pivotally mounted on the casing having either of its forks co-operatively connecting with one of the rolls and imparting an intermittent motion thereto, and a single lever having yieldable connections with the detent for operating the same to cause the forks to impart intermittent motions to the rolls.

18. In a label printing machine, a casing, a label printing mechanism therein including a label guide, said guide being constructed from a single piece of sheet metal bent upon itself causing it to be formed into upper and lower parts between which the label passes, said upper and lower parts having elongated rectangular openings through which the type bar of the printing member of said mechanism may engage, a platen roller under the guide for receiving the impression of the type bar through said openings, the lower part of the guide having a flange overlying the upper part thereby

23 relatively spacing said parts, and attaching ears carried by the guide for securing the same to the base of the casing.

19. In a label printing machine, a casing, 5 a label receiving means in the bottom of the casing, a printing ribbon passing over the label receiving means, said casing having guides in its opposite side walls, a U-shaped member mounted in said guide, a 10 printing element mounted in bearings of the U-shaped member, said printing element having transversely extending grooves, a spring detent carried by the U-shaped member and provided with a roller engaging said grooves for holding the element in position when imparting an impression on the label, means for retaining the U-shaped member to its normal raised position.

20. In a label printing machine, a casing, 20 a label printing mechanism in the casing including a printing cylinder movable in a plane with the casing, ribbon supporting rolls, a printing ribbon engaging said rolls, an escapement detent having coöperative 25 connections with either of said rolls for imparting an intermittent motion to said rolls,

said detent being movable with the printing cylinder, whereby as the cylinder moves upwardly, as a result of a depression movement, an intermittent motion is imparted to 30 one or the other of said rolls.

21. In a label printing machine, a casing, a label printing mechanism in the casing including a printing cylinder movable in a plane with the casing, ribbon supporting 35 rolls, a printing ribbon engaging said rolls, an escapement detent having coöperative connections with either of said rolls for imparting an intermittent motion to said rolls, 40 said detent being movable with the printing cylinder, whereby as the cylinder moves upwardly, which is a result of a depression movement, an intermittent motion is imparted to one or the other of said rolls, and means operatively connecting with the escapement detent for shifting the same 45 whereby either of said rolls may be given an intermittent motion.

In testimony whereof I hereunto affix my signature.

HUGH F. HURST.
